John N. Johnson INVENTOR.

BY

Rosenbaum, Stockbridge & Cook
ATTORNEYS.

UNITED STATES PATENT OFFICE.

JOHN N. JOHNSON, OF ALBUQUERQUE, NEW MEXICO.

SAFETY RAZOR.

Application filed May 22, 1920. Serial No. 383,373.

To all whom it may concern:

Be it known that I, JOHN N. JOHNSON, a citizen of the United States, residing at Albuquerque, in the county of Bernalillo and State of New Mexico, have invented certain new and useful Improvements in Safety Razors, of which the following is a full, clear, and exact description.

This invention relates to power operated razors, and particularly to safety razors in which the blade is given a very rapid cutting movement.

An object of my invention is to provide a safety razor of this type in which the cutting blade at each movement will be shifted in a direction oblique to its cutting edge and thus simulate the movement given an ordinary razor in use.

A further object is to provide a safety razor which can be adjusted to cut more or less closely, as desired, without changing the angle of inclination of the blade to the surface to be shaved.

A further object is to provide a power operated razor in which the rate of the cutting movements can be varied at will within certain limits.

A further object is to provide a razor of the above type which is simple and compact in construction, convenient, safe and efficient in operation, and inexpensive to manufacture.

Other objects and advantages will be apparent from the following description, and the novel features of my invention will be particularly pointed out in claims.

In the drawings:

Fig. 1 is an elevation partly in section of a razor in which my invention has been embodied;

Fig. 2 is a section substantially along the line *a—a* of Fig. 1;

Fig. 3 is a section substantially along the line *b—b* of Fig. 1;

Fig. 4 is a section substantially along the line *c—c* of Fig. 2;

Fig. 5 is an elevation of certain of the details;

Fig. 6 is a section substantially along the line *d—d* of Fig. 5;

Fig. 7 is a section substantially along the line *e—e* of Fig. 1;

Fig. 8 is a longitudinal section of the handle and illustrating the motor carried there-in;

Fig. 9 is a front elevation of the blade cover plate which acts as a rear guard;

Fig. 10 is a sectional elevation of the same, and

Fig. 11 is an elevation of a modification of certain details.

In the illustrated embodiment, the support or body 1 is provided with an extension 2 forming an advance or forward guard, and an upstanding wall 3. A tubular handle 4 is detachably connected to body or support 1 by any suitable means such as screws 5. Secured to one face of the wall 3 is a pair of parallel V-shaped guides 6 and 7, with the apex of each guide pointing toward the other. A vibrating or blade carrying frame or member 8 is provided upon its rear face or wall 9 with a similar pair of parallel V-shaped guides 10 and 11 having the apexes of the guides pointing toward each other and also having the corresponding guides upon the walls 3 and 9 in telescopic position, as indicated in the drawing, so that the frame 8 can slide or reciprocate upon the wall 3 of the support 1 due to the sliding of the guides 10 and 11 upon guides 6 and 7. If desired, one of the guides 6 or 7, or both, may have a portion of one end bent to form a stop lug 6^a for limiting the movement in a cutting direction by contact with the end of the corresponding guide, as indicated in Fig. 11.

The forward face or wall 12 of the frame 8 is provided with two parallel rows of lugs or guides 13 and 14 extending outwardly therefrom to guide a blade carrier plate 15 for reciprocation thereon. This plate 15 carries at one edge thereof a projecting lug 16 in position to be engaged and cammed in one direction by a screw 17 adjustably carried by a lug 18 extending forwardly from the face 12 of the frame. The face 12 is also provided with ears 19 extending therefrom to which ears 20 upon a cover plate 21 are pivoted by screw pins 22 carried by the latter. A leaf spring 23 is secured intermediate of its ends to the lug 16 of the plate 15 and has its ends bowed outwardly and disposed against the rear face of the ears 19 whereby the spring normally tends to shift the plate 15 in opposition to the screw 17. Thus upon operation of the screw 17 the plate 15 will be shifted in one direction or the other in accordance with the direction of operation of the screw. The ears 20 of the cover 21 each have an angular corner 110

105

100

105

110

at the junction of the ears and cover, which are in engagement with the ends of the spring so that by the engagement of the spring with either face of the angular corner, the cover will be yieldingly held either in open position as indicated by dotted lines in Fig. 6, or in the closed position indicated by the full lines in Fig. 6. The ears 19 are provided with rearward extensions 24 which engage over one edge of the spring 23 and prevent any edgewise displacement from operative position behind the ears. Lugs 25 on opposite sides of the plate 15 are adapted to engage with the lugs 13 and 14 and limit excessive movement of the plate upon the wall 12. The plate 15 is provided with lugs 26, preferably struck up therefrom, which receive apertures 27 in a removable and reversible double-edged cutter or razor blade 28 and support the latter thereon. The forward or free edge of the cover plate 21 when in closed position, engages with the blade 28 adjacent to its forward cutting edge and holds the blade firmly against the plate 15. A spring 29 carried on the under side of the cover plate also engages with another portion of the blade 28 and assists in holding it against plate 15. In order to simulate the most efficient manual movement employed in handling an ordinary razor, and give the cutting edge of the blade 28 a simultaneous or combined forward and endwise movement, the guides 6, 7, 10 and 11 are arranged non-parallel to and non-perpendicular to the cutting edge of the blade, so as to cause the movement upon the support 1 or wall 3 to be in a direction inclined to the cutting edge of the blade. During the cutting movements the cover plate 21 moves with the frame 8 and blade 28, and acts as a rear guard. Adjustment of the screw 17 will thrust the forward cutting edge of the blade 28 varying extents through the space between the two guards to cause the blade to make a light or close-cut as desired, the blade 28, plate 15 and wall 12 being inclined to the surface being shaved and to the wall 3 or plane of the guides, by an angle preferably approximating 20° which is the angle at which an ordinary razor blade is commonly presented to the surface being shaved.

The means for imparting vibratory movements to the frame and blade comprises a motor upon or within the tubular handle 4 and having an operating member extending therefrom into operative engagement with the frame. A base piece 30 of soft iron, extends along one wall of the handle 4 a short distance, then crosses to and extends along the other wall in the same direction, and has in the cross over portion a short section 31 parallel with the end sections. Upon the inside faces of the base piece 30 are a plurality of electromagnets 32 and 33, the electromagnets 32 being disposed upon the sec-

tion of the base piece extending along one wall of the handle and the electromagnets 33 being disposed upon the section of the base piece extending along the opposite wall of the handle. The free ends of the electromagnets thus face in opposite directions. The armature bar 34 is pivoted intermediate its ends by pivot 35 in the short section 31 of the base piece 30, and is bent to extend along the free ends of the electromagnets, being provided with a cross over section 36 for this purpose. The electromagnets 32 and 33 will, when energized, pull upon the armature to rotate the same in one direction, such rotation being opposed by a flexible and resilient extension 37 of the armature which engages with an abutment or stop 38 that may or may not be adjustably carried by the handle 4. This arrangement of electromagnets provides the most efficient pull upon the armature when a series of electromagnets are employed in a small linear space. The end 39 of the armature which is opposite from the end extension 37, extends beyond handle 4, passes through a clearance opening 40 in the wall 3 of the support 1, and engages operably in an aperture 41 in a plate 42 extending transversely between and secured to the guides 10 and 11 of the frame, whereby oscillation of the armature about its pivot 35 will produce vibratory movements of the frame 8 and blade 28 upon the support 1. The electromagnets and armature 34 are disposed in a plane parallel with the guides 6, 7, 10 and 11, so that oscillation of the end 39 of the armature will be in a direction parallel with the movement of the frame on the guides and thereby prevent binding and insure a free action. The aperture 41 in the plate 42 may conveniently be formed by striking up lugs 43 therefrom, the lugs acting as resilient clamps upon the armature end 39 and preventing lost motion between the same.

Beneath the extension 37 and in alignment therewith, the handle 4 is provided with an elongated aperture or slot 44. A layer of insulation 45 is provided with a slot 46 aligned with slot 44 and also carries thereon a somewhat U-shaped spring contact 47, the free end of which extends upwardly at an acute angle to the extension 37. The free end of the contact 47 carries a contact piece 48 which is adapted at times to engage with a similar contact piece 49 upon the under side of the extension 37. The contact 47 is connected by a wire 50 to a terminal plate 51 and to which one circuit wire 52 coming from the source of current 53 is connected. A post 54 is slidably mounted upon the inside of the handle by means of a screw 55 threaded therein and passing through the aligned slots 44 and 46 with the head upon the outside of the handle. A spring plate 56 disposed between the screw head and handle 130

provides frictional means for securing the post 54 in any adjusted position along the slots. The post 54 is provided with a tail piece 57 for holding the same upright, and a depending strip 58 upon the lower face of the post slides in the slots and prevents turning of the post about the screw as a pivot. The post has threaded through its upper end and parallel with the walls of the handle 10 a screw 59 having an insulated tip 60 thereon for engagement with the contact 47. Thus if the post is stationary the screw can be operated to cam the contact 47 into operative position with respect to the extension 37 or permit of its retraction from that position, or the post can be shifted along the slot to cause the screw which moves therewith to cam the contact 47 into operative position with respect to the extension or to release the 15 contact and permit it to spring away from the extension. In order to facilitate shifting movements of the post 54, the spring plate 20 56 may have a knurled depression 61 therein for finger engagement. A wire 62 leads from the other terminal of the source of current 25 53 to the electromagnets the latter being connected in series or parallel, with their other terminals grounded to the handle 4, or base piece 30 whereby the connection to the extension 37 is secured. The current passes from battery 53, through wire 52, plate 51, wire 50, contact 47, extension 37 and the frame of the handle to the electromagnets, and then through wire 62 back to the 30 35 battery or other source of current. The circuit is of course, made and broken between contact points 48 and 49.

In operation the cover plate 21 is lifted, a sharp blade 28 placed in position upon plate 40 15, the cover plate closed, and the razor connected to source of current 53. If now the plate 56 is shifted to the left, (Figs. 1 and 8) the post 54 and screw 59 will be shifted also, and tip 60 of the screw will cam the contact 47 into operative position with respect to the extension 37, which latter, due to its reaction with the abutment 38 holds the armature at its extreme position away from the electromagnets. Engagement of 45 50 the contact points 48 and 49 causes energization of the electromagnets and consequent attraction of the armature. Movement of the armature carries with it the extension 37 and the circuit is broken at contacts 48 and 49. During the movement of the armature towards the electromagnets, the extension 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

extent to which the contact 47 will be shifted, and the nearer to the extension the contact point 48 is shifted, the shorter will be the throw or stroke of the armature, with the result that the speed or rate of vibration of the armature and cutting blade will be increased. Conversely adjustment of the screw in the opposite direction will decrease the rate of vibration and increase the stroke of the armature, both increase and decrease, of course, being only within certain limits. When one desires to stop the motor, the plate 56 and post 54 are shifted along the slot to the right (Figs. 1 and 8) and contact 47 when thus released springs down and opens the circuit.

It will be obvious that various changes and modifications may be made in the embodiment herein described and illustrated within the principle and scope of my invention.

I claim:

1. A safety razor comprising a support having a forward guard and a wall portion, stationary guides on said wall portion, a frame provided with guides co-operating with the stationary guides for movement along the same, a blade carried by the frame and disposed at an acute angle with respect to the plane of the guides, means on the frame for adjusting the blade toward and from the plane of the guides, means on the support for causing movement of said frame and blade upon the stationary guides, and a cover for the blade carried by the frame and acting as a rear guard.

2. A safety razor comprising a support having a forward guard and a wall portion, a frame mounted on the wall portion for repeated short movements in alternate directions, a plate carried by the frame for adjustment toward or from the wall portion, a blade carried by the plate, a cover hinged to the frame and holding the blade in position on the plate, said cover also serving as a rear guard, and means on the support for causing said repeated short movements of the frame and blade.

3. A safety razor comprising a support having a forward guard and a wall portion, a frame mounted on the wall portion for repeated short movements in alternate directions, a plate carried by the frame for adjustment toward or from the wall portion, a blade carried by the plate, a cover hinged to the frame and engaging with one portion of the blade for holding the same in position on the plate, a spring member carried by the cover and engaging another portion of the blade to yieldingly hold it against the plate, and means on the support for causing said repeated short movements of the frame and blade.

4. In a safety razor, a support having a forward guard and a rear guard, a plate

slidable on said support toward or from the forward guard, a spring normally tending to retract said plate from the forward guard, means adjustable on said support for forcing said plate toward the guard, a cutting blade carried by the plate for movement therewith in the space between the guards to be shifted outwardly when a close cut is desired and inwardly when a light cut is de-

10 sired.

5. In a safety razor, a support having a forward guard, a carrier mounted for movement on said support, a rear guard secured to the carrier for movement therewith, a 15 blade mounted on said carrier with its cutting edge extending between the front and rear guards, and means on the carrier for shifting said blade to variable extents through the space between the guards for 20 causing a light or close shave.

6. In a safety razor, a support having a member provided with lugs extending outwardly from one face thereof, and arranged in two spaced rows, a plate slidable on the 25 member between the rows of lugs, means for limiting movement of the plate in one direction, a spring reacting between the supporting member and the plate for shifting the plate in the opposite direction, means adjustable on the member for shifting the plate in said one direction against the action of the spring, a removable cutting blade carried by the plate, and front and rear guards carried by the support with the blade between 30 them.

7. In a safety razor, a supporting frame, a plate slidable on the frame, a spring reacting between the plate and frame for shifting the plate on the frame in one direction, 40 means adjustable on the frame for shifting the plate against the action of the spring, a cover plate hinged to the frame and co-acting with said spring to be yieldingly held in either open or closed position, a removable cutting blade carried by the plate for movement therewith and having its cutting edge extending beyond the edge of the cover plate when the latter is in closed position, supporting means for the frame having a 45 guard disposed adjacent the face of the blade opposite to that adjacent the cover plate, the adjustment of the plate and blade upon the frame projecting the cutting edge of the blade through the space between the cover plate 50 and guard to a greater or less extent whereby a light or close cut may be obtained when the razor is used.

8. In a safety razor, a carrier having up- 60 standing ears and also spaced guiding means thereon, a plate mounted to slide on the carrier between the spaced guiding means, a spring strip secured intermediate of its ends to said plate, and having its ends bearing against said ears to exert a force on said 65 plate tending to move the latter in one direc-

tion between the guiding means, a member adjustably carried by said carrier for shifting the plate variable extents between the guiding means in opposition to the spring strip, a cutting blade carried by the plate, and a cover forming a rear guard hinged to said ears and acting when closed upon the blade to prevent removal of the blade from the plate.

9. In a safety razor, a carrier having up- 70 standing ears and also spaced guiding means thereon, a plate mounted to slide on the carrier between the spaced guiding means, a spring strip secured intermediate of its ends to said plate, and having its ends bearing against said ears to exert a force on said plate tending to move the latter in one direction between the guiding means, a member adjustably carried by said carrier for shifting the plate variable extents between the guiding means in opposition to the spring strip, 75 a cutting blade carried by the plate, and a cover forming a rear guard hinged to said ears and acting when closed upon the blade to prevent removal of the blade from the plate.

80

10. In a safety razor, a carrier having up- 85 standing ears and also spaced guiding means thereon, a plate mounted to slide on the carrier between the spaced guiding means, a spring strip secured intermediate of its ends to said plate, and having its ends bearing against said ears to exert a force on said plate tending to move the latter in one direction between the guiding means, a member adjustably carried by said carrier for shifting the plate variable extents between the guiding means in opposition to the spring strip, a cutting blade carried by the plate, and a cover forming a rear guard hinged to said ears and acting when closed upon the blade to prevent removal of the blade from the plate, said cover having angular corners engaging with the ends of the spring strip whereby the cover will be yieldingly held in either open or closed position.

95

11. In a safety razor, a carrier having up- 100 standing ears and also spaced guiding means thereon, a plate mounted to slide on the carrier between the spaced guiding means, a spring strip secured intermediate of its ends to said plate, and having its ends bearing against said ears to exert a force on said plate tending to move the latter in one direction between the guiding means, a member adjustably carried by said carrier for shifting the plate variable extents between the guiding means in opposition to the spring strip, a cutting blade carried by the plate, and a cover forming a rear guard hinged to said ears and acting when closed upon the blade adjacent its forward edge to prevent removal of the blade from the plate, and resilient means carried by the under side of the cover for engaging with rear portion of the top face of the blade to hold it flatly against the plate.

105

12. In a safety razor, a carrier having up- 110 standing ears and also spaced guiding means thereon, a plate mounted to slide on the carrier between the spaced guiding means, a spring strip secured intermediate of its ends to said plate, and having its ends bearing against said ears to exert a force on said plate tending to move the latter in one direction between the guiding means, a member adjustably carried by said carrier for shifting the plate variable extents between the guiding means in opposition to the spring strip, a cutting blade carried by the plate, and a cover forming a rear guard hinged to said ears and acting 115

125

130

when closed upon the blade adjacent its forward end to prevent removal of the blade from the plate, and resilient means carried by the under side of the cover for engaging with rear portion of the top face of the blade to hold it flatly against the plate, said cover having angular corners engaging with the ends of the spring strip whereby the cover will be yieldingly held in either

10 open or closed position.

12. In a safety razor having front and rear guards, a blade having a cutting edge, a carrier device for said blade mounted for vibratory movement in a direction substantially parallel with a plane tangent to the outer faces of the guards, said carrier device having a portion adjustable thereon to thrust the cutting edge of the blade through variable extents obliquely toward

20 and from said plane and means for causing vibratory movements of said carrier device.

13. A safety razor comprising a support having a forward guard, guides carried by the support and extending in a plane parallel to the effective edge of the guard, said guides being also oblique to the edge of the guard, a frame mounted in said guides for movement on the support, and a cutting blade carried by the frame with its face making an angle of approximately 20° with the plane of the guides and with its edge parallel with the edge of the guard, a rear guard carried by the frame, and means

carried by the handle for causing repeated movements of the frame in the guides. 35

14. A safety razor comprising a support, having a front guard thereon, a carrier frame mounted for movement thereon, a cutting blade mounted on the carrier frame with its cutting edge oblique to the direction of movement of the carrier frame and with the blade disposed in a plane making an angle of approximately 20° with the plane of movement of the carrier frame, 40 a rear guard carried by the carrier frame and movable therewith, and means for causing movements of the carrier frame upon the support. 45

15. In a safety razor, a support having a forward guard, a plate slidably mounted on said support, a cutting blade removably carried by the plate, a cover pivoted to the support forming a rear guard when closed against the blade and holding the cutting blade upon the plate, means carried by the support and adjustable to force the plate and blade in one direction upon the support, and a single spring carried by the plate and acting upon the cover to oppose the movement of the plate by the said means and 50 acting to resiliently hold the cover in either its open or closed position. 55

In witness whereof, I hereunto subscribe my signature.

JOHN N. JOHNSON.
